UNITED STATES PATENT OFFICE.

CLARENCE M. SYMONDS, OF SAN ANSELMO, CALIFORNIA, ASSIGNOR TO AMERICAN CAN COMPANY, OF SAN FRANCISCO, CALIFORNIA, A CORPORATION OF NEW JERSEY.

APPARATUS FOR CUTTING AND APPLYING RING-LINERS TO THE FLANGES OF CAN ENDS.

1,328,020.

Specification of Letters Patent. Patented Jan. 13, 1920.

Application filed January 29, 1916. Serial No. 75,038.

To all whom it may concern:

Be it known that I, CLARENCE M. SYMONDS, a citizen of the United States, residing at San Anselmo, in the county of Marin and State of California, have invented certain new and useful Improvements in Apparatus for Cutting and Applying Ring-Liners to the Flanges of Can Ends, of which the following is a specification.

- 10 The present invention relates to a machine for cutting ring liners from a continuous web or blank, and applying the same to the flanges of positioned can ends, and has for its object the provision of a 15 machine for this purpose, simple of construction, and which necessitates the use of relatively few moving parts, particularly those to which reciprocating motion must be imparted.
- 20 To this end the invention comprises broadly associated instrumentalities for cutting a disk blank from a continuous web, for cutting a ring liner from said blank, and for applying said ring liner to the flange of 25 a can end in axial alignment therewith, interworking in timed relation with devices for holding and carrying the blank and ring liner, and means for positioning a can end in proper relation thereto for the reception 30 of said liner.

In order to more fully comprehend the invention, a preferred embodiment of which is hereinafter described, reference should be had to the accompanying sheets of drawings 35 wherein—

Figure 1 is a front elevation of the complete machine.

Fig. 2 is a vertical section taken on the line $x-x$ of Fig. 1, and viewed in the direction of the arrows.

Fig. 3 is a horizontal section taken on the line $y-y$ of Fig. 1, and viewed in the direction of the arrows.

Fig. 4 is a detailed vertical section, enlarged, taken on the line $s-s$ of Fig. 3, and viewed in the direction of the arrows.

Fig. 5 is a detailed vertical section, enlarged, taken on the line $t-t$ of Fig. 3, and viewed in the direction of the arrows.

Fig. 6 is an enlarged detailed vertical section taken on the line $u-u$ of Fig. 3, and viewed in the direction of the arrows.

Fig. 7 is an enlarged detailed vertical section taken on the line $w-w$ of Fig. 3, and viewed in the direction of the arrows.

55

In the drawings, the reference numerals 1 designate the spaced upright side members of a suitably constructed supporting frame, which side members are united together and held in spaced relation by a cross member 2 at their lower portions, a similar cross member 3 at their upper portions, and between said cross members by vertically disposed webs 4 and 5, and a horizontally disposed table 6.

65

Power for operating the moving parts of the machine is applied to a horizontal shaft 7, rotatably mounted in the upper portion of the frame, by means of a belt pulley 8 fixed thereon. It is to be understood, however, that any suitable form of driving means may be employed. The horizontal drive shaft 7 transmits its rotary motion by means of a vertical shaft 9, Fig. 1 of the drawings, to a second horizontal shaft 10 70 suitably journaled in the lower portion of the frame. Said shafts 7 and 10 are so related that they rotate in unison.

75

The upper shaft 7 carries a crank 11, Figs. 1 and 2 of the drawings, which imparts vertical reciprocating motion, through a connecting rod 12, to a head 13, slidably mounted upon the upper web 5 of the frame, and retained in position by suitable guides 14. This head 13 has an enlarged lower portion 15, which carries a series of depending dies, shown at 16, 17 and 18 respectively, in Fig. 1 of the drawings, and which will be more fully described hereinafter. In a similar manner the lower shaft 10 carries a crank 19, which imparts vertical reciprocating motion, through a connecting rod 20, to a head 21, slidably mounted in suitable guides 22 80 upon the lower web 4 of the frame. Said head 21 carries upon its upper end a die ring 23, Figs. 2 and 5 of the drawings, adapted to coact with the die 17, through an opening 6' in the table 6, for a purpose to be 85

more fully described hereinafter. In a similar manner the lower shaft 10 carries a crank 19, which imparts vertical reciprocating motion, through a connecting rod 20, to a head 21, slidably mounted in suitable guides 22 upon the lower web 4 of the frame. Said head 21 carries upon its upper end a die ring 23, Figs. 2 and 5 of the drawings, adapted to coact with the die 17, through an opening 6' in the table 6, for a purpose to be 90 later set forth.

95

A horizontally disposed turret 24 is rotatably mounted above the table 6 and beneath the upper reciprocating head 13. Said turret is formed with a plurality of vertical openings 25 therein, there being four of said 100

openings illustrated, in Fig. 3 of the drawings, although their number is limited only by structural considerations. Each opening 25 is formed, as shown in Figs. 4 and 5 of the drawings, with an annular shoulder 26. The turret 24 is fixed to and carried by the upper end of a vertically disposed shaft 27, Figs. 1 and 2 of the drawings, which is suitably journaled in the frame, and upon 10 the lower end of which is fixed a spur gear 28, adapted to mesh with a similar gear 29 fixed upon the lower end of a second vertical shaft 30. This latter shaft 30 is rotated intermittently from the lower horizontal 15 shaft 10, by means of coacting mutilated worm gears 31 and 32, in such relation that for every complete revolution of the horizontal shafts 7 and 10, the turret 24 is turned to bring one of the openings 25 therein into 20 axial alignment with the die 16, that is, in the particular machine herein illustrated, one quarter of a revolution.

The web 33 of paper or other material from which the ring liners are to be cut is 25 shown in Figs. 3 and 4 of the drawings, as carried upon a spool or roll 34, and led in a horizontal direction across the machine immediately above a plate 35, which is secured at 36 to the table 6, extending over the turret 24, and provided with an opening 37 in which is mounted a stationary die ring 38, of a size suitable to coat with the reciprocating die 16, as shown in Fig. 4 of the drawings. The web 33 is then passed between a 35 feed roller 39 and an idler roller 40, the former being intermittently rotated by the turret shaft 27 through the agency of the short geared shafts 41 and 42, to intermittently feed said web through the machine 40 at the proper rate.

It will be seen by reference to Fig. 4 of the drawings, that the die 16, being forced down into the coacting stationary die ring 38, cuts a circular disk 43 from the interposed web 33, and deposits said disk on the annular flange 26 within the opening 25 in the turret 24. It is understood, of course, that during this disk cutting operation, said turret 24 is stationary. Immediately following the raising of the die 16, however, the turret 24 is moved one step forward, thus carrying the disk 43 from the position A to the position B,—Fig. 3 of the drawings, in which latter position it is in axial alignment with the upper reciprocating die 17 and the coacting lower reciprocating die ring 23,—Figs. 2 and 5 of the drawings.

The upper die 17 is encircled by a stripper ring 44, which has a limited range of 60 vertical movement thereupon, and which is normally held at the lowermost limit of said movement by springs 45. The upper die 17 and the lower die ring 23 are moved simultaneously in opposite directions by their respective operating mechanisms hereinbefore

described, with the result that an annular ring 46, Fig. 5 of the drawings, is sheared from the disk 43 lying within the opening 25 in the turret 24. The central cut out disk 47 is pressed downward through the die ring 70 23 and drops through the hollow reciprocating head 21 to a suitable place of deposit, not shown in the drawings. The coacting die and die ring 17 and 23 are then separated, and the stripper ring 44 removes the 75 cut ring liner 46 from the die 17, and leaves the same deposited on the shoulder 26 of the opening 25 of the turret 24. Said turret 24 is then advanced another step, to bring the opening 25 with the cut ring liner 46 therein to the position C in Fig. 3 of the drawings, where it is in vertical alignment with the third upper reciprocating die 18.

Fixed upon the upper end of the vertical intermittently rotated shaft 30, above the 85 table 6 and underlying a portion of the turret 24, is a second turret 48,—Figs. 1, 3, 6 and 7 of the drawings, formed with circular openings 49, shown as four in number, and of a size suitable to admit a can end 50. A 90 holder 51, adapted to contain a stack of said can ends 50, is mounted on the table 6 adjacent the turret 48. Associated with the lower portion of said holder are a pair of swinging cutout arms 52,—Fig. 3 of the drawings, adapted to raise and support the stack of ends with the exception of the lowermost one thereof, and a horizontally reciprocating feed slide 53, operated by means of a cam 54, Fig. 1 of the drawings, on the 100 lower continuously rotating shaft 10, and a lever 55. Said feed slide 53 moves the lowermost freed can end from the holder 51 through one of the radially disposed grooves or slots 56 in the under side of the turret 105 48 until said can end lies within one of the openings 49, at the position D in Fig. 3 of the drawings.

A circumferential groove 57 is also formed in the under side of the turret 48, which lies over a circular guide rail 58, secured to the table 6, and formed with an opening 59 adjacent the holder 51, through which the ends 50 are pushed by the feed slide 53. Thus it will be seen that a can end 50, seated 110 within one of the circular openings 49 in the turret 48, will be carried around over the surface of the table 6 by the movement of said turret and will be prevented from escaping through the slot 56 by the guide 115 rail 58.

In this manner a can end 50 is carried to the position C, Fig. 3 of the drawings, where it rests upon the table 6 below and in vertical alignment with the ring liner 46 which 125 is supported within the opening 25 in the turret 24. During a period of rest of both turrets, the upper reciprocating head 13 is moved downward to bring the assembling die 18 down through the openings 25 and 130

49 in the turrets 24 and 48 respectively, and to force the ring liner 46 from its seat 26 in the opening 25 down onto the flange of the alined can end 50, as shown in Fig. 5 6 of the drawings.

At the next step in the rotation of the turret 48, the can end 50, with its assembled ring liner 46, is carried to the position E, Fig. 3 of the drawings, at which point there 10 is an opening 60 in the table 6, through which said lined can end drops, and from which it is carried as by a chute 61, Figs. 3 and 7 of the drawings, to a suitable place of deposit not illustrated.

15 It is to be noted that in the preferred form of the constructed apparatus, the blank cutting die 16, the ring cutting die 17 and the assembling die 18, are carried by an upper reciprocating head 13, and therefore 20 work in unison; and furthermore that the turrets 24 and 48 are rotated an amount equal to the angular distance between adjacent openings,—that is 90 degrees in the present case,—after each complete stroke of 25 the reciprocating head 13. Therefore at every stroke of said head, a blank is cut from the web at A in Fig. 3 of the drawings, a ring liner is cut from a blank at B, a ring liner is applied to a can end at C, an unlined 30 can end is fed from the holder at D, and a lined end is discharged from the machine at E. The die ring 23, carried by the lower reciprocating head 21, coöperates only with the ring cutting die 17 at the position B.

35 The invention has herein been described and illustrated in its preferred form. I do not wish to limit myself thereto, however, for the reason that many changes may be made in the machine as illustrated without 40 departing in any manner from the spirit of the invention, and it is therefore my wish to be understood as claiming the invention as broadly as the art will permit.

Having thus described my invention, 45 what I claim as new and desire to protect by Letters Patent is:—

1. In a machine for cutting ring liners from a web and applying the same to the flanges of can ends, the same comprising 50 associated instrumentalities for cutting a blank from a web and from said blank cutting a ring liner, horizontally rotating means having shouldered openings for conveying the ring liner to an assembling station, devices for positioning a can end in axial alinement with the ring liner, and means for applying the ring liner to the flange of the alined can end.

2. In a machine for the described purpose, the same comprising cutting stations and an assembling station, means at successive cutting stations for cutting from a web a blank and severing therefrom a ring liner, horizontally rotating means having 65 shouldered openings for transferring the

ring liner to the assembling station of the machine, devices situated at the assembling station for moving a can end into axial alinement with the transferred ring liner, and reciprocating means situated at the assembling station for applying the ring liner 70 to the flange of the can end.

3. In a machine for the described purpose, the combination with a rotatable turret provided with a series of shouldered vertically 75 disposed openings, of co-acting instrumentalities for cutting from a web a blank and severing from said blank a ring liner, and depositing the said ring liner within one of the openings of the rotatable turret, means 80 for advancing the said turret to position the ring liner at the assembling station, devices for positioning a can end in axial alinement with the ring liner, and reciprocating means for assembling the ring liner with respect to the flange of the positioned can end. 85

4. In an apparatus for the described purpose, the combination with means for intermittently feeding a web, of a primary cutter for cutting from said web a disk blank, 90 a secondary cutter for severing from said disk blank a ring liner, carrier means for transferring the disk from the primary cutter to the secondary cutter and the ring liner from the secondary cutter to an assembling station, means for feeding a can end into axial alinement with the transferred ring liner, and reciprocating devices for applying the ring liner to the flange of 95 the said can end. 100

5. In a machine for the described purpose, a horizontally rotatable turret having a plurality of spaced vertical interiorly shouldered openings therein, means for positioning and feeding a web in superposed relation thereto, reciprocating devices for successively cutting disk blanks from said web, severing a ring liner from each disk blank, and depositing said ring liner within one of the shouldered openings in said turret; a 105 second horizontally rotatable turret having a series of spaced vertical openings therein, a holder adapted to contain a stack of can ends, means for successively delivering the lowermost can end of said stack into an 110 opening of said second turret; mechanism for intermittently actuating said turrets to successively position said ring liners in axial alinement with said can ends, and means associated with said cutting devices for successively assembling the ring liners and can 115 ends so positioned. 120

6. In a machine for the described purpose, a horizontally rotatable turret having a plurality of spaced vertical interiorly shouldered openings therein, means for positioning and feeding a web in superposed relation thereto, a reciprocating die for cutting a disk blank from said web and depositing the same within one of the shouldered openings 125 130

in said turret, a second reciprocating die for severing a ring liner from said disk blank without removing the same from said turret; a second horizontally rotatable turret 5 having a series of spaced vertical openings therein, a holder adapted to contain a supply of can ends, means for delivering a can end from said holder to an opening in said second turret; mechanism for intermittently 10 actuating said turrets to position said ring liner and said can end in axial alinement, reciprocating devices for assembling said ring liner and said can end, and a reciprocating head carrying said cutting dies and 15 said assembling devices to cause the same to operate in unison.

7. In a machine for the described purpose, a reciprocating die for cutting a disk blank from a positioned web, a pair of oppositely operating coacting dies for severing a ring liner from said disk blank, a reciprocating die for assembling said ring liner with the flange of a positioned can end, a horizontally rotatable turret for 20 transferring the disk blank from the blank cutting die to the ring cutting dies, and for transferring the ring liner from the ring cutting dies to the assembling die, a second horizontally rotatable turret for delivering 25 a can end into axial alinement with the ring liner beneath said assembling die, and associated mechanism for actuating the mentioned dies and turrets in timed relation.

8. In a machine for cutting and applying 30 ring liners, the combination of dies for cutting the exterior periphery of the liner, means for feeding liner material to said dies, a carrier having shouldered recesses in which the disks so cut are received and conveyed, means at a further station of said carrier for cutting the cores from said disks and leaving the ring liners in said recesses, means for feeding can ends to an applying 35 station of said carrier and below the said shouldered recesses, and means for forcing the ring liners on to said can ends.

9. In a machine for the described purpose, a horizontally rotatable turret having a plurality of spaced vertical interiorly shouldered openings therein, means for positioning and feeding flat liner material in superposed relation thereto, reciprocating devices for successively cutting disk blanks from 40 said flat liner material, severing a ring liner from each disk blank, and depositing said ring liner within one of the shouldered openings in said turret; a second horizontally rotatable turret having a series of spaced vertical openings therein, a holder adapted to 45 contain a stack of can ends, means for successively delivering the lowermost can end of said stack into an opening of said second turret; mechanism for intermittently actuating said turrets to successively position said 50 ring liners in axial alinement with said can

ends, and means associated with said cutting devices for successively assembling the ring liners and can ends so positioned.

10. In a machine for the described purpose, a horizontally rotatable turret having a plurality of spaced vertical interiorly shouldered openings therein, means for positioning and feeding flat liner material in superposed relation thereto, a reciprocating die for cutting a disk blank from said flat 75 liner material and depositing the same within one of the shouldered openings in said turret, a second reciprocating die for severing a ring liner from said disk blank without removing the same from said turret; a second 80 horizontally rotatable turret having a series of spaced vertical openings therein, a holder adapted to contain a supply of can ends, means for delivering a can end from said holder to an opening in said second turret; 85 mechanism for intermittently actuating said turrets to position said ring liner and said can end in axial alinement, reciprocating devices for assembling said ring liner and said can end, and a reciprocating head carrying 90 said cutting dies and said assembling devices to cause the same to operate in unison.

11. In a machine for the described purpose, a reciprocating die for cutting a disk blank from positioned flat liner material, a 95 pair of oppositely operating coacting dies for severing a ring liner from said disk blank, a reciprocating die for assembling said ring liner with the flange of a positioned can end, a horizontally rotatable turret for 100 transferring the disk blank from the blank cutting die to the ring cutting dies and for transferring the ring liner from the ring cutting dies to the assembling die, a second horizontally rotatable turret for delivering 105 a can end into axial alinement with the ring liner beneath said assembling die, and associated mechanism for actuating the mentioned dies and turrets in timed relation.

12. In a machine for cutting and applying ring liners, the combination of a reciprocating head carrying in spaced locations means for cutting the exterior of a liner and depositing the disk so formed and means for cutting the interior of a liner and depositing the liner so formed and means for applying a cut liner to a can end, an intermittently rotatable turret having spaced shouldered orifices adapted to receive and carry said disk and liner, means for feeding 110 flat liner material to said exterior cutting means, and means for feeding can ends in alinement with said applying means.

In testimony whereof I have signed my name to this specification in the presence of 125 two subscribing witnesses.

CLARENCE M. SYMONDS.
